UNITED STATES PATENT OFFICE.

WALTER E. PIPER, OF MELROSE, MASSACHUSETTS, ASSIGNOR TO BOSTON RUBBER SHOE COMPANY, A CORPORATION OF MASSACHUSETTS.

ART OF MANUFACTURING RUBBER FOOTWEAR.

1,158,389.

Specification of Letters Patent. Patented Oct. 26, 1915.

Application filed March 19, 1913. Serial No. 755,416.

To all whom it may concern:

Be it known that I, WALTER E. PIPER, a citizen of the United States, and resident of Melrose, in the county of Middlesex and State of Massachusetts, have invented an Improvement in the Art of Manufacturing Rubber Footwear, of which the following description, in connection with the accompanying drawings, is a specification, like 10 letters on the drawings representing like parts.

My invention relates to the process of manufacturing rubber footwear, and its object is to afford an improved process and to 15 perfect the product.

In the manufacture of rubber footwear as now ordinarily carried out in large factories, it is customary to assemble the lining, upper, reinforcing pieces, and sole successively upon a last by hand, and, in order 20 properly to conform these various parts of the shoe to the last a number of hand operations are necessary. The insole and lining, having been first stamped out and applied 25 by hand to a last, are subjected to a rolling operation, in order to conform them, at the edge of the sole where the lining overlaps the insole, to the irregular contour of the last on which they are positioned. This rolling 30 is accomplished by a hand operation, the operator using a small steel cylindrical roll having a straight surface and endeavoring to make the lining fit smoothly and evenly, without wrinkles or any unevennesses, by 35 manipulating the straight surface of the roller over the contour of the last and thus "lasting" the lining thereon. Then the reinforcing pieces, if any, such as counter, pipings or strips around the edge portion, 40 toe-cap, etc., are applied by hand, and each is successively rolled to make it fit and conform smoothly in its respective position.

It will be understood that in making rubber footwear, the various layers constituting 45 the shoe or overshoe are prepared from plastic and sticky stock which, together with the outer rubber coating and the subsequent vulcanizing operation, constitute the sole means of holding the various layers together, no sewing or other processes being 50 usually required. Therefore, the various successive hand rolling operations just described are of great importance, not only in smoothing and conforming the layers to the 55 shape of the last on which they are assem-

bled, but also in rendering the layers intimately connected and stuck together in a substantially homogeneous article. Considerable pressure is therefore necessary in the rolling operation to insure satisfactory results. With the lining and other layers thus prepared, the rubber upper is then applied and it is similarly rolled by hand and the lower edges of the upper are turned over and folded or crimped onto the innersole, 60 the outsole then being applied and also rolled. A still further rolling operation is required in the ordinary process which is of great importance and consists in forcing the edge portion of the outsole, cut on a bevel 65 for this purpose, over against the upper to make a firm and water-tight joint, which is afterward completed by the vulcanizing process.

During the various hand operations of 75 rolling, the various layers, including the rubber upper itself, are apt to be displaced, the rolling action naturally tending to move, shove, or cause an unsatisfactory product. Great difficulty has also been found heretofore in seeing that the operators rolled over 80 every part of the surface, as such operators, ordinarily being employed on "piece-work", are anxious to turn out a large number of pairs, being more interested in quantity than 85 quality, and therefore are liable to slight the very important rolling operations. It will also be seen that, by reason of these hand operations and the repeated and continual hand rolling, the hand labor required 90 in present methods is unduly great for this step of manufacturing. Furthermore, it is difficult for a roller having a straight edge 95 to make the layers conform suitably to the varying curved contours of a shoe last, and great skill is required in this hand rolling operation in order to secure a first-class article. A still further objection is that an operator does not always perform this rolling work with the same degree of strength, 100 and hence it is impossible to secure a uniformity of product under the method above outlined.

My present process obviates entirely the 105 objections and difficulties above noted, and provides an automatic step in the process of making rubber footwear which accomplishes in one simple operation the same work heretofore done by the various hand rolling operations.

An important feature in my process also is that the output of a uniform product is rendered possible, and that every part of the work is subjected to exactly the degree of pressure required, without any portion being slighted, and without any tendency to displace the various parts or to cause them to "creep." My process also may be carried out by means of unskilled labor and 10 with great economy of time, space, and expense. Furthermore, my method, by producing a more firmly compressed and uniformly made shoe or rubber, especially at the joint between the upper and outsole, 15 facilitates the solidifying of the rubber in the subsequent vulcanizing process.

In carrying out my improved process, I preferably subject the completely assembled shoe, overshoe or the like to pressure applied simultaneously throughout the entire contour of the upper and sole after the various layers have been assembled. By placing the last and assembled materials in a mold having flexible or yieldable diaphragms which automatically conform to the varying contour of the last when pressure is applied on the outside of said diaphragms, I am enabled to practise my process economically and expeditiously. Preferably two diaphragms will be employed, one shaped roughly to fit the upper, and a lower diaphragm formed roughly to fit the sole or bottom portion of the shoe, and by applying fluid pressure, such as by any 30 pneumatic or hydraulic means, to the exterior of said diaphragms, the several layers comprising the rubber shoe are firmly, evenly, and simultaneously compacted into a substantially homogeneous article and at 35 a single operation. Any desired degree of pressure can be applied, and may be maintained for such length of time as will best suit the work being treated.

I have discovered that by applying pressure to the outer surface of the series of layers of materials comprising the rubber shoe, while still upon the last, and by forcing out all the air contained either between the shoe materials and the last, or impregnating 45 the various layers, that I am enabled to produce a more firmly compacted and formed shoe, greatly increasing the cohesion of the various layers and preparing the entire shoe in the best possible manner for the vulcanizing process. It is, therefore, an important feature of my present process, to allow or provide for the escape of the air contained between the flexible diaphragms as they are forced into contact with the shoe upper 50 materials during the application of fluid pressure on the outside of said diaphragms. Preferably, therefore, the air is allowed to escape freely as it is forced out of the molding apparatus by the continued inflation of 60 the rubber diaphragms. When the air is 65

thus substantially forced out, it will be readily appreciated that I am enabled to secure the advantages of the full amount of pressure exerted on the shoe materials for the purpose of compacting the same, the pressure applied upon the outer surface of the diaphragms not being counteracted by any atmospheric pressure which was at first present, owing to the air contained between the diaphragms before they were forced into 70 intimate contact about the shoe. I am aware that the vulcanization of rubber footwear has been accomplished under pressure, but I believe it to be a distinct novelty as a process of preparing rubber footwear for vulcanization, to exclude the air between the 75 last and shoe materials as well as between the layers of such materials by the application of pressure upon the outer surface of the said materials. It will be readily appreciated that such atmospheric pressure amounting to approximately fifteen pounds per square inch is of very material extent, and by using a pressure of, say, twenty 80 pounds per square inch on the outer surfaces 85 of the diaphragms to exclude the air, I am enabled to obtain the advantages of a greatly increased effect when the air has been actually excluded.

Suitable apparatus to carry out my improved method is shown in copending applications Serial Nos. 755,414, filed Mar. 19, 1913, and 786,318, filed August 23, 1913, and I will now explain the further carrying out of the process by means of the apparatus 90 described and claimed in said copending application.

Referring to the accompanying drawings, illustrating a portion of the apparatus as shown in one of the said copending applications, Figure 1 is a longitudinal view in section, with a shoe in position therein, of a molding apparatus; and Fig. 2 is a view on a reduced scale of the mold, a part being shown in section on the line 2-2 of Fig. 1. 105

This apparatus comprises a lower member 1, preferably of iron or metal, and an upper member 2 pivoted at 3 on suitable lugs 4 formed on the lower member 1, and both being supported on a bench or the like 115 5. The lower member 1 has a bed or depression 6 formed therein at the right hand end, viewing Fig. 2, and the upper member has a dome 7 formed thereon and adapted to cover and register with the depression 6 in the lower member when the upper member 2 is swung on the pivot 3 to contact with the member 1 in the position shown in Fig. 2. The pivotal connection 3 between the members 1 and 2 allows the upper member to be swung upward so that a lasted shoe may be placed by the operator 120 as will be hereinafter described. The lower open portion of the dome 7 is formed with a flange 8 constituting a rim throughout the 130

periphery of the dome, and secured to this flange by means of a ring 9 of corresponding area and contour to the rim 8 by a plurality of set screws 10, is the edge portion 5 of a yielding diaphragm 11. The diaphragm 11 is preferably of rubber and is formed roughly in the contour of a shoe upper projecting into the dome 7, as clearly illustrated in Figs. 1 and 2. The screws 10 10 are countersunk in the rim 9 wherever the same may be positioned, and are correspondingly tapped into the flange 8 of the dome 7 so that the outer surface of the ring 9 presents a smooth surface. A corresponding 15 diaphragm 12 of rubber or the like is secured to the rim 13 of the bed 6 by a ring 14 in a similar manner to that just described as holding the diaphragm 11 to the rim of the dome 7. This lower diaphragm 12 is 20 formed in the outline of a shoe sole, having a transverse rib 15, which is substantially in position to fit the shoe shank or arch to be acted upon. The rings 9 and 14 are of equal 25 area and contour and as the upper member 2 is lowered into the position shown in Fig. 2, the rim 9 of the dome is arranged to rest upon the ring 14 and thus to support the dome in lowered position. Preferably, the 30 members 1 and 2 may be locked together, in any suitable way, or the weight of the member 2 may be sufficient to hold it in contact with the lower member 1 during the operation of the apparatus. The dome 7 and the bed 6 are provided with ports 16 and 17 35 respectively to receive from any suitable source of power (not shown) the fluid pressure, either pneumatic or hydraulic, being adaptable for use therein. I preferably employ a pneumatic pressure, but also contemplate the use of fluid pressure in the 40 lower portion of the mold contained in the bed 6, and pneumatic pressure in the dome 7. Pressure being applied to the dome and bed through the ports 16 and 17 respectively, the diaphragms 11 and 12 are 45 correspondingly forced in a direction toward each other. If a last 19 and its assembled shoe materials 20 are positioned within the mold, it will be readily seen that the diaphragms 11 and 12 will fold about the last 50 during the admission of pressure in the ports 16 and 17, the yielding nature of these diaphragms causing them to automatically conform to a wide range in size or style of 55 last and shoe contained therein. This affords means for the application of pressure throughout the entire extent of the rubber shoe. Any desired degree of pressure may be supplied, and therefore the various 60 layers comprising the shoe 20 can be simultaneously forced into intimate and homogeneous contact, smoothing out all wrinkles and taking the place of the former rolling operations already mentioned. By 65 applying pressure simultaneously, the va-

rious layers comprising the shoe are not displaced and are, in fact, more firmly and densely compacted than by a mere rolling, where the pressure is applied only momentarily during the passing of the roller. By 70 my process I am enabled to apply and maintain any desired degree of pressure for any desired length of time until the shoe materials have set in a suitable manner. It is within the scope of my process to 75 either provide hand controlled mechanism to supply, maintain and release the pressure in the mold, or to provide automatic means which will apply and maintain the desired amount of pressure for a predetermined time, and then automatically release the same, which means would also be adjustable 80 for varying grades and styles of work.

In carrying out my process, the insole, lining, counter, piping, upper and outer sole are all applied to the last in the usual order and in the customary manner, but without the rolling operation, or with only sufficient hand rolling to hold the various 85 layers in place. It will be readily understood by those skilled in the art, that the various materials or layers comprising rubber footwear instantly adhere when assembled and therefore but little or no rolling is required to hold these materials in their respective positions. The operator then raises the upper member 2 and places the shoe with the upper materials thereon within the mold, resting the same upon the lower diaphragm 12 and utilizing the rib 15 as a means to 90 position the shoe longitudinally within the bed 6 and dome 7. The member 2 and dome 7 will then be lowered until the ring 9 thereof rests upon the ring 14 of the bed 6, when the same may be locked together if desired. 95 Pressure being now applied through the ports 16 and 17, the diaphragms 11 and 12 respectively are expanded and automatically fit about the shoe, as just explained, during the continuous application of pressure, until 100 the desired degree of force is maintained within the mold. I find that some twenty to thirty pounds pressure per square inch is productive of best results in the manufacture of light weight rubber overshoes, although of course a greater or a less degree 105 may be found best for different styles and grades of footwear, and the materials used therein. With twenty pounds pressure the rubber shoe will be ordinarily contained 110 within the mold only momentarily, and the pressure may then be released and the dome 7 lifted and the shoe removed, being then ready for the vulcanizing process. The contacting surfaces of rings 9 and 14 are, of 115 course, not air tight, and thus all the air contained between the diaphragms 11 and 12 and between the shoe materials 20 and last 19 will readily escape through the said 120 contacting surfaces during the operations 130

just described. Air is, of course, contained within any wrinkles or unevennesses between the various adjacent layers, and between the layers as a whole and the last, and the pressure applied to the outer layers must force this contained air from between the diaphragms and out of the molding apparatus. When the air pressure is released and the diaphragms tend to return to their normal form, the air will again rush through the contacting surfaces of the rings 9 and 14, and thus enable the dome to be lifted easily, and the shoe just operated upon removed. I am thus enabled to secure a more uniform product than has ever been possible heretofore through the hand rolling operations and to effect the compacting of the various layers in a much more satisfactory manner than heretofore. Also the danger of displacing the various layers or having them move or "creep", as during hand rolling, is substantially eliminated. Furthermore, no part of the surface of the shoe is slighted or omitted and pressure is applied evenly and uniformly to the entire shoe surface throughout the irregular contour of the last, irrespective of the style, or model, in the manner best suited for the parts being treated.

30 I find that in carrying out my novel process, as above described, the heretofore difficult operation of rolling the edge of the outer sole upon and against the upper is performed most advantageously, and automatically, a firm and tight joint being insured at this important edge of the shoe, thus facilitating a water-tight joint between outer sole and upper. Preferably I so arrange the diaphragms 11 and 12 that the greatest elasticity and yielding, and therefore a better and closer fitting, will be secured at the most important portions of the shoe. Thus at and around the toe portion and in the shank of the shoe, especially, it is desirable that the diaphragm should fit accurately and that substantially a greater elasticity be present than in other parts. This can be accomplished by making the diaphragms 11 and 12 of greater elasticity at the points mentioned in any desired way, that herein shown being to make the diaphragms of less thickness at these points. By having the diaphragms 11 and 12 of a considerable elasticity, I am able to operate with the same apparatus upon a great range of different sizes, styles and shapes of foot wear, as the yielding diaphragms automatically conform to such sizes, styles and shapes of lasts without being especially made for operating upon any one size or form. Thus, in carrying out my process, a child's overshoe and a man's overshoe may be successively placed in the mold for operation without any change in the diaphragms. The advantages of my novel process will be apparent

as the hand labor heretofore required in this step in the manufacture of rubber footwear is substantially eliminated, and a much better, more uniform and evenly compacted shoe is produced for the subsequent step of vulcanization. By having a duplex molding apparatus, one shoe can be left subjected to the desired pressure, while the operator is removing a prior shoe and replacing another, this being an economical method of operation and one which affords considerable practical advantages in the practice of my invention.

The process whereby rubber shoe materials are firmly compacted by applying pressure to the outer surfaces by means of a mold or the like, which pressure is applied simultaneously throughout the entire extent as a step in preparing the rubber shoe for the vulcanizing process, is, so far as I am aware, 80 a distinct novelty in this art, and therefore I desire to claim the same broadly. Furthermore, the application of pressure through means which tends to also exclude the air between the outer layer and the last 90 on which the shoe materials are assembled thus securing the entire advantages of the whole amount of pressure applied to said outer surface for the purpose of compacting the various shoe layers, is also believed to be 95 a distinct novelty.

My process consists in the application of pressure to take the place of the hand rolling operations heretofore required; to secure a more homogeneous and cohesive mass in 100 the exact form and contour of the last by an instantaneous operation; and to apply pressure in the manner described, as a step in preparing the rubber footwear for vulcanization, and these features I wish to claim 105 broadly.

Having described my invention, what I claim as new and desire to secure by Letters Patent is:

1. The improvement in the art of manufacturing rubber shoes which consists in assembling to lightly adhere to each other upon a last the several layers that comprise a completed shoe ready for vulcanization, and then applying compacting pressure simultaneously to the entire exposed outer surface of the completed shoe upon the last. 110

2. The improvement in the art of manufacturing rubber shoes which consists in assembling to lightly adhere to each other upon a last the several layers that comprise a completed shoe ready for vulcanization, and then applying compacting pressure simultaneously and substantially of uniform amount to the entire exposed outer surface 115 of the completed shoe upon the last. 120

3. The improvement in the art of manufacturing rubber shoes which consists in assembling to lightly adhere to each other upon a last the several layers that comprise 125

5 a completed shoe ready for vulcanization, and then applying compacting pressure to the entire exposed outer surface of the completed shoe upon the last by means of a flexible medium arranged to conform automatically to the contour of said completed shoe.

4. The improvement in the art of manufacturing rubber shoes which consists in assembling to lightly adhere to each other 10 upon a last the several layers that comprise a completed shoe ready for vulcanization, and then applying compacting pressure to the entire exposed outer surface of the completed shoe upon the last by means of a yielding medium of predetermined varying flexibility.

5. The improvement in the art of manufacturing rubber shoes which consists in assembling to lightly adhere to each other 20 upon a last the several layers that comprise a completed shoe ready for vulcanization, then applying compacting pressure simultaneously to the entire exposed outer sur-

face of the completed shoe upon the last, and simultaneously permitting the en- 25 trapped air contained within said completed shoe to escape.

6. That improvement in the art of manufacturing rubber shoes which consists in assembling the layers of materials constituting the shoe, comprising the inner sole, lining, counter, piping, upper and outer sole, upon a last without rolling said layers separately and subjecting them to pressure applied to the outer surface of the outer layers sufficient to compact the layers into the completed shoe ready for the subsequent 30 35 vulcanizing process.

In testimony whereof, I have signed my name to this specification; in the presence of 40 two subscribing witnesses.

WALTER E. PIPER.
